UNITED STATES PATENT OFFICE.

CHARLES F. BUTTE, OF SAN FRANCISCO, CALIFORNIA, ASSIGNOR TO PAUL C. F. BUTTE, OF SAN FRANCISCO, CALIFORNIA.

AUTOMATIC ELECTRIC SWITCH.

SPECIFICATION forming part of Letters Patent No. 692,005, dated January 28, 1902.

Application filed May 1, 1901. Serial No. 58,257. (No model.)

To all whom it may concern:

Be it known that I, CHARLES F. BUTTE, a citizen of the United States, residing in the city and county of San Francisco, State of California, have invented an Improvement in Automatic Electric Switches; and I hereby declare the following to be a full, clear, and exact description of the same.

My invention relates to an improved device for connecting or disconnecting electric circuits, and which I term an "automatic switch."

It consists of a base carrying a latch-lever and armature, an electromagnet and a tube, a spring and sleeve which are slidable over the tube. The sleeve contains a recess, with which the latch-lever engages when the spring is compressed, thereby locking the sleeve and holding the spring at tension and retaining switch in desired position. The electromagnet when energized acts upon the latch-lever to release the same, thereby releasing the sleeve and allowing the spring to force the switch to connect or disconnect the circuit.

My invention also comprises details of construction, which will be more fully explained by reference to the accompanying drawings, in which—

Figure 1 is a view showing the plug inserted into the board-socket, the spring compressed, and the latch and sleeve engaged. Fig. 2 shows the plug disengaged from the socket and the parts in their normal position. Fig. 3 is a sectional view at right angles to Fig. 1, showing the parts in their normal position. Fig. 4 is a diagrammatic view showing the connection of a pair of plugs with relay and common battery.

I have in the present illustration shown my invention as applied to a telephone-switchboard in which plugs are introduced into sockets to make connections between subscribers, and when the plugs are removed from the sockets the connection is broken.

It is the object of my invention to provide a means to automatically remove the plugs when the connection is no longer desired.

In my drawings I have only illustrated so much of the device as is necessary to explain my improvement, the construction of the or-

dinary switchboard being well understood and not materially changed.

The tube 1 is fastened into the base 2, which forms one terminal of the plug and to which is connected one wire of the cord 7 by means of the screw 20. Within the tube 1 and insulated therefrom and from the base by insulating-bushings 3, so as not to have any connection therewith, is the rod or stem 4, Fig. 3. This stem 4 has a head 5, formed with or fixed to it, which forms the other terminal of the plug. At the other end of the stem 4 is a nut 6, which fastens the stem 4 with relation to the tube 1. To this end of stem 4 is fastened the other terminal of cord 7, thereby completing the circuit from the plug-tip and sleeve.

On the tube 1 are a sleeve 8 and spring 9, which are free to slide thereon. The sleeve 8 is slotted or channeled on one side, as shown at 10, and a pin 11, fixed to the tube 1, enters slot 10 and acts as a guide to keep the sleeve 8 in alignment with the base 2 when sliding and also acts a stop both for the sleeve 8 and the distance the plug can be inserted into socket. The action of the spring 9 is always against the base 2 and the sleeve 8. Therefore the normal condition of the plug is with the sleeve 8 always against the pin 11, which, as before stated, acts as a stop. In order to maintain the plug in position against the action of spring 9 to force it out when inserted into a socket, the recess or catch 12 on sleeve 8 will engage with the latch 13 when the plug has been inserted into the socket, thereby locking the sleeve and maintaining the spring in tension. The latch 13 is carried upon the end of lever 15, which is fulcrumed in base 2, as shown at 14, and its other end forms or carries an armature, as at 16. The electromagnet 17 is so located with relation to the armature 16 that when the electromagnet is energized it will immediately attract the armature 16, thereby causing lever 15 to tilt on its fulcrum 14, and thus disengage the latch 13 from the recess or catch 12 of the sleeve 8. The releasing of the latch 13 from the recess or catch 12 allows the spring 9 to act upon sleeve 8, which rests against the face of the socket in board A, thus forcing the plug from

the socket, and the plug will then fall to its place on the table of the switch-board by means of a roller-weight hung upon the cord 7 in the usual manner.

5. The connection of the relay, Fig. 4, with relation to the main lines of the subscriber's telephone may be in the same manner as the clearing-out drop of the present system, or the circuits of the switch may be applied to 10 any telephone system when certain conditions have been complied with, which are within the knowledge of any one skilled in the art.

The electromagnet 17 is energized by means of a common battery, which is thrown into 15 circuit when the subscriber "hangs up" or "rings off," or the circuit of battery through electromagnet 17 may be completed in other manner within the knowledge of any one skilled in the art.

20. While I have described this device in its application to telephone-switchboards, it will be understood it is applicable in any connection where it is desirable to automatically connect or disconnect a circuit when certain conditions have been complied with, and such arrangements of the device as will answer the 25 conditions are within the knowledge of any one skilled in the art. I do not therefore limit myself to the exact mechanism herein shown or to the application of the device to 30 telephone-switchboards.

Having thus described my invention, what I claim as new, and desire to secure by Letters Patent, is—

35. 1. An automatic electric switch including a plug having spring-pressed circuit making and breaking devices, a latching mechanism therefor carried thereby, a socket into which the head of the plug is inserted whereby the

spring is compressed and the latch engaged 40 simultaneously, means completing an electrical circuit when the plug is inserted, and means for disengaging the latch.

2. An automatic electric switch comprising a plug, having spring-pressed circuit making 45 and breaking devices, a retaining-latch therefor carried thereby, electrical connections, and a socket into which the plug is inserted whereby an electrical circuit is completed, the spring compressed and the latch engaged 50 simultaneously, and an electrically-actuated device for disengaging the latch, said device carried by the plug.

3. An automatic electric switch consisting of a stem with a contact-making head, a tube 55 concentric with and insulated therefrom, and a base by which they are carried, a sleeve slideable on the tube and a spring acting to normally force it forward, a latch by which the sleeve is engaged when retracted, and an electromagnet carried by the switch and acting when energized to release the latch.

4. An automatic electric switch including a plug having a stem with a contact-making head, a socket into which said head is inserted, electrical contacts, a spring encircling said stem and acting to disengage the head, and compressed when the head is inserted, a latch by which the spring is retained under tension, and an electromagnet by which the latch is 70 disengaged, said latch and magnet carried by the plug.

In witness whereof I have hereunto set my hand.

CHARLES F. BUTTE.
